CLAIM

I claim the ornamental design for a landscaping tool, as shown and described.

DESCRIPTION

FIG. 1 is a perspective view of a landscaping tool; FIG. 2 is a top plan view of the landscaping tool of FIG. 1; FIG. 3 is a bottom plan view of the landscaping tool of FIG. 1;

FIG. 4 is a front elevation view of the landscaping tool of FIG. 1, which is identical to the rear elevation view; FIG. 5 is a left side elevation view of the landscaping tool of FIG. 1, which is identical to the right side elevation view; FIG. 6 is a perspective view of a landscaping tool according to another embodiment of the invention;

FIG. 7 is a top plan view of the landscaping tool of FIG. 6; FIG. 8 is a bottom plan view of the landscaping tool of FIG. 6;

FIG. 9 is a front elevation view of the landscaping tool of FIG. 6, which is identical to the rear elevation view; and, FIG. 10 is a left side elevation view of the landscaping tool of FIG. 6, which is identical to the right side elevation view. Portions of the drawings shown in broken lines illustrate parts of the landscaping tool that form no part of the claimed design.

1 Claim, 8 Drawing Sheets
